CLAIM

The ornamental design for a table, as shown and described.

DESCRIPTION

FIG. 1 is a top plan view of a table according to the present invention;

FIG. 2 is a side elevational view, with the opposite side being a mirror image thereof; and,

FIG. 3 is an end elevational view, with the opposite side being a mirror image thereof.

The broken lines are for illustrative purposes only and form no part of the claimed design.
